JOHN COLLINSON, OF MANCHESTER, ENGLAND, ASSIGNOR TO WESTINGHOUSE ELECTRIC
AND MANUFACTURING COMPANY, A CORPORATION OF PENNSYLVANIA.

ELECTRICAL RESISTANCE.

1,332,030.

Specification of Letters Patent. Patented Feb. 24, 1920.

Application filed September 9, 1916. Serial No. 119,319.

To all whom it may concern:

Be it known that I, JOHN COLLINSON, a subject of the King of Great Britain, and a resident of Manchester, in the county of 5 Lancaster, England, have invented a new and useful Improvement in Electrical Resistances, of which the following is a specification.

My invention relates to electrical resistors 10 of the "grid" type, and it has for its object to provide an improved construction of grid for use in resistance devices of this type.

It has heretofore been proposed to provide an electrical resistance device of the 15 grid type constructed from a strip of sheet metal in which a number of transverse cuts or slits are made by passing the sheet through a punching press or rolls, such as are used for the production of "expanded" 20 metal, the sheet being used as an electrical resistance in the condition in which it comes from the punching press or rolls, that is, without being expanded.

According to my present invention, a grid 25 resistance is formed from a strip of sheet metal which is transversely corrugated and in which a number of cuts or slits, extending parallel to the corrugations, are made by any suitable means. By reason of the 30 transverse corrugations, the grid is considerably strengthened and made more compact in the longitudinal direction relatively to an uncorrugated grid of the same current-carrying capacity constructed from 35 sheet metal.

The invention is illustrated in the accompanying drawing, in which Figure 1 is an edgewise view of a corrugated strip of sheet metal from which an electrical grid resistance is constructed according to the present 40 invention; Fig. 2 is a plan view of the grid resistance shown in Fig. 1, illustrating a suitable arrangement of transverse cuts or slits in the said strip; Fig. 3 is an enlarged 45 sectional view taken on the line III—III of Fig. 2, illustrating a preferred construction; Fig. 4 is a plan view of two half corrugations constructed in the manner illustrated in Fig. 3.

Referring to the drawings, a strip of 50 sheet metal 1, consisting of any desired metal having the required electrical conductivity, is provided with transverse corrugations 2 by means of any suitable corrugating

device, and along the crests of the corrugations, cuts or slits 3 are provided in order to increase the resistance of the strip. The operations of corrugating the metal strip 1 and of forming therein the cuts or slits 2 may be performed separately by successive 60 operations; or they may be carried out simultaneously by one and the same operation, by passing the sheet 1 through suitable corrugating and punching rolls.

In the preferred form of the invention 65 shown in Fig. 3, one side 4 of each cut or slit 3 is bent away from the opposite side, this arrangement being adapted to prevent the opposite sides of the cuts from coming into contact and so causing short circuits.

Uncut or uncorrugated portions 5 are left at each end of a grid so as to enable the latter to be easily secured in position in a 70 resistance frame or box.

I claim as my invention:

1. An electric-resistance element comprising a slotted and corrugated sheet of conducting material, several of the slots being unconnected and disposed in alinement.

2. An electric-resistance element comprising a sheet of conducting material provided with a plurality of alined, unconnected slots having edges laterally displaced with reference to the body of the sheet.

3. An electric-resistance element comprising a sheet of conducting material provided with a plurality of corrugations and with slots extending along the crests of said corrugations.

4. An electric-resistance element comprising a sheet of conducting material provided with parallel corrugations and with a plurality of slots extending substantially along the crests of said corrugations one of each of the adjacent edges being depressed.

5. An electric-resistance element comprising a sheet of conducting material provided with parallel corrugations and with slots disposed in staggered relation and extending substantially parallel to the said corrugations and to each other.

6. An electric-resistance element comprising a sheet of conducting material provided with parallel corrugations and with slots extending along the crests of the said corrugations.

7. An electric-resistance element comprising a sheet of conducting material provided

with parallel corrugations and with slots extending along the crests of the said corrugations and having their adjacent edges bent out of contact with each other.

- 5 8. An electric-resistance element comprising a sheet of conducting material having flat end portions and an intermediate portion provided with parallel corrugations and with slots disposed in staggered relation and 10 extending substantially parallel to the said corrugations and to each other, the said slots having their adjacent edges bent out of contact with each other.

9. An electric-resistance element comprising 15 a corrugated sheet of conducting material having a plurality of unconnected slots extending along the crests of the corrugations.

10. An electric-resistance element comprising 20 a corrugated sheet of conducting material having a plurality of unconnected slots extending along the crests of the corrugations, one edge of each of said slots being depressed.

25 11. An electric-resistance element comprising a sheet of conducting material having the general contour of a predetermined surface and provided with slots, one edge of each of several of said slots lying in said

surface and the other edge lying outside of 30 said surface.

12. An electric-resistance element comprising a sheet of conducting material provided with slots, certain of said slots having their adjacent edges bent in one direction 35 out of contact with each other and certain other of said slots having their edges bent in another direction out of contact with each other.

13. An electric-resistance element comprising 40 a corrugated sheet of conducting material having staggered slots.

14. An electric-resistance element comprising a sheet of conducting material having 45 slots, the opposite edges of certain of said slots being laterally displaced to different degrees with respect to said sheet.

15. An electric-resistance element comprising a sheet of conducting material having 50 a plurality of laterally displaced portions each provided with an opening.

In testimony whereof, I have hereunto subscribed my name this tenth day of August, 1916.

JOHN COLLINSON.
